(57) **CLAIM**

The ornamental design for a sports bottle, as shown and described.

DESCRIPTION

FIG. 1 is a front perspective view of a sports bottle, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is an enlarged detail view of area 9 in FIG. 2.
The broken lines in the drawings illustrate the portions of the sports bottle, which form no part of the claimed design.
The dash-dot-dash broken lines encircling the enlarged views are for annotative purposes only and form no part of the claim thereof.
